Beaver Pipe Tools Inc., Warren, Ohio, a cor-
poration of Ohio

Application February 15, 1939, Serial No. 83,001

Term of patent 14 years

To all whom it may concern:

Be it known that I, Robert B. Pealer, a citizen of the United States of America, residing at Warren, in the county of Trumbull and State of Ohio, have invented a new, original, and ornamental Design for an Electric Power Drive Unit for Use with Hand Cutting Tools, of which the following is a specification, reference being had to the accompanying drawing, forming part thereof

Fig. 1 is a perspective view of an end and one

side of the electric power drive unit for use with hand cutting tools embodying my new design; and

Fig. 2 is a perspective view of the other end and side thereof.

I claim:

The ornamental design for an electric power drive unit for use with hand cutting tools, substantially as shown.

ROBERT B. PEALER.
